US00D966241S

(12) **United States Design Patent** (10) **Patent No.:** **US D966,241 S**
(45) **Date of Patent:** **** Oct. 11, 2022**

(54) **ANTENNA**

(71) Applicant: **KMW INC.**, Hwaseong-si (KR)

(72) Inventors: **Duk Yong Kim**, Yongin-si (KR); **Kyu Chul Choi**, Hwaseong-si (KR); **In Hwa Choi**, Yongin-si (KR); **Youn Jun Cho**, Hwaseong-si (KR); **Jae Hyun Park**, Hwaseong-si (KR); **Kyo Sung Ji**, Hwaseong-si (KR); **Hye Yeon Kim**, Hwaseong-si (KR); **Chi Back Ryu**, Hwaseong-si (KR); **Jeong Hyun Choi**, Hwaseong-si (KR)

(73) Assignee: **KMW INC.**, Hwaseong-si (KR)

(**) Term: **15 Years**

(21) Appl. No.: **29/755,315**

(22) Filed: **Oct. 19, 2020**

(30) **Foreign Application Priority Data**

Apr. 20, 2020 (KR) 30-2020-0017456

(51) **LOC (13) Cl.** **14-03**

(52) **U.S. Cl.**

USPC **D14/230**

CLAIM

We claim the ornamental design for the antenna, as shown and described.

DESCRIPTION

FIG. 1 is a perspective view of an antenna showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof; and,

FIG. 7 is a bottom view thereof.

The features shown in broken lines in the various Figures are for illustrating environment structure and form no part of the claimed design.

1 Claim, 7 Drawing Sheets
